DRAPERY PLEATER CLIP

Clarence T. Bryant, 49 Park St., North Wilmington, Mass.

Filed Jan. 12, 1962, Ser. No. 68,285

Term of patent 7 years

(Cl. D17—12)

I claim:

The ornamental design for a drapery pleater clip, as shown.
